UNITED STATES PATENT OFFICE.

JOSEPH A. WHITE, OF PHILADELPHIA, PENNSYLVANIA, ASSIGNOR TO THE MOORE AND WHITE COMPANY, OF PHILADELPHIA, PENNSYLVANIA, A CORPORATION OF PENNSYLVANIA.

LAY-BOY.

1,057,601.

Specification of Letters Patent.

Patented Apr. 1, 1913.

Application filed August 10, 1911. Serial No. 643,325.

To all whom it may concern:

Be it known that I, JOSEPH A. WHITE, a citizen of the United States, residing in Philadelphia, Pennsylvania, have invented 5 certain Improvements in Lay-Boys, of which the following is a specification.

My invention relates to certain improvements in means for automatically controlling the position of the feeding mechanism 10 in relation to the pile of paper of a "lay-boy" used in piling paper as it comes from a cutting machine.

The invention also relates to certain details of construction, which will be fully 15 described hereafter, reference being had to the accompanying drawing, in which:—

While my invention is particularly adapted as a lay-boy used in connection with mechanical means for feeding paper to a pile, 20 it will be understood that the invention can be used for piling paper by hand, or by any suitable apparatus, as the main object of the invention is to provide an apparatus in which the top of the pile will be on substantially the same level, the pile receding as 25 the paper is added to it. This is particularly of advantage in piling by hand, as the operator placing the paper on the pile does not have to alter his position.

30 Figure 1, is a side view of my improved lay-boy; showing it in position in respect to the cutters which sever the continuous web of paper, forming sheets which are properly piled; Fig. 2, is an end view; Fig. 3, 35 is an enlarged side view partly in section, showing the details of the pneumatic mechanism for controlling the position of the pile of sheets in respect to the feeding mechanism; Fig. 4, is a sectional view on the line 40 4—4, Fig. 3; Fig. 5, is a sectional view, drawn to an enlarged scale, on the line 5—5, Fig. 2; Fig. 6, is an enlarged view of part of Fig. 2, and Fig. 7, is a view illustrating a modification of the invention.

45 A is the frame of the lay-boy.

B is the platform upon which the paper α is piled. This platform is suspended from shafts B' on which are chain drums b. Chains b' extend from the drums and are attached to eyes b² through which pass bars B². These bars extend under the platform B and properly support the platform in position. As the paper is piled upon the platform, the platform is automatically lowered

5 by mechanism which will be described hereafter and which turns the shafts B'. The shafts are supported in suitable bearings secured to the upper portion A' of the frame A.

E is a truck having wheels e—e and this 60 truck passes under the platform B. When the pile of paper has reached the height desired, the platform B is lowered on to the projecting ribs e' of the truck and transferred to any point desired.

C—C are the feed rollers, which carry the web of paper from the paper making machine or from a reel, as desired.

c c' are the cutters, which cut the web of paper into sheets of the desired length. The 70 length of the sheet may be varied by increasing or diminishing the speed of the cutter c.

D and F are endless belts between which the sheets of paper are gripped and conveyed to the pile. The belt D passes around drums d d'—d², while the belt F passes around drums f—f'. The drums d² and f' are mounted on adjustable bearings so as to increase or diminish the tension of the belts. 80 The paper, as it is cut, is gripped between the two belts D and F and is fed forward on to the pile, as indicated at α ; the paper coming in contact with a stop g on a depending frame G and held laterally in position 85 by guards g' and h.

i is a jogger which is moved toward and from the pile of paper being, in the present instance, mounted on a rock shaft I, driven in any suitable manner. There is a 90 set of guards g' and h on each side of the machine and there is also a jogger on each side. Thus, the paper is evenly piled upon the platform B.

In order to always maintain the discharge 95 end of the belts D and F in proper relation to the upper surface of the pile, I arrange automatic means for lowering the pile as it increases. This is accomplished by a suction apparatus, which I will now proceed to 100 describe.

N is a suction pump, of any suitable type, and connected to the suction end of the pump is a pipe n, which communicates with a pipe n', Fig. 3 leading to a suction 105 chamber formed by two cupped disks M and mounted between the disks is a diaphragm m of any suitable material. The

pipe n' also communicates with a pipe n^2 attached to the guide h , as clearly illustrated in Figs. 3 and 4, and there is a port h' in this guide which may be closed, or partly closed, by the paper α as it is piled upon the platform B. When the pile of paper is below the port h' , then the suction pump freely draws air through the pipe n^2 , without affecting the diaphragm, but as soon as the paper commences to close the port, as in Fig. 4, then the supply of air to the pump is less than the capacity of the pump and the suction will draw the diaphragm down and as this diaphragm controls the feed mechanism it will allow said feed mechanism to operate to lower the platform and the pile of paper, and will insure the opening of the port h' so as to give the suction pump more air, after which the feed mechanism will stop until the opening is again contracted. In the present instance, the diaphragm m is connected to a rod m' , which bears against the under side of the weighted arm k of a two-armed lever K pivoted at k' and adjustably mounted on a rod m' are nuts m^2 , which bear against the under side of the arm k . By turning these nuts the movement of the lever K can be regulated. On the rod m' are thumb nuts m^3 and between the thumb nuts and the upper casing M is a spring m^4 and by adjusting the thumb nuts on the rods, the tension of the spring can be regulated so as to place more or less resistance on the suction pump.

On the arm k^2 of the lever K is a pawl p , which engages the teeth of a ratchet wheel P secured to the shaft P' and on this shaft is a sprocket wheel P^2 and passing around this sprocket wheel is a chain P' . The chain also passes around a sprocket wheel R on a shaft R' . On the shaft R' are two worms s , one at each side of the machine, which mesh with the worm wheels s' on the shafts B' so that as the shaft P' is turned motion will be imparted to the shafts B' causing the platform B to be lowered. In order to impart feeding motion to the pawl p , I provide an eccentric t on a shaft T.

T' is an eccentric strap, which passes around the eccentric t and is connected at its outer end to an arm p^2 on the pawl p . When the diaphragm is in its normal position, the pawl is in its forward position and must return in order to feed the ratchet wheel P forward. It will be seen that the eccentric t has only a limited movement and will not actuate the pawl until it is moved by the drawing down of the diaphragm M and releasing the weighted bell crank lever. As soon as the bell crank lever is released, then the eccentric will cause the pawl p to turn the shaft P' through the medium of the ratchet wheel any number of teeth desired, according to the particular throw of the eccentric. The shaft T is operated from the

main power shaft W through belting leading to a pulley on the shaft T', which, in turn, is carried to the shaft T. In the present instance, the suction pump N is also driven from the shaft W.

In order to adjust the stop g to conform to the length of the sheets to be piled, I make the suspended frame G adjustable and in the present instance I provide two racks G', which are suitably mounted on the overhanging frame A'. The teeth of these racks are on the under side and meshing with the teeth are pinions g^2 , which are mounted on a shaft G^2 carried by the frame G and on the inner end of each shaft G^2 is a hand wheel g^3 by which the shaft is turned so that on turning the shaft, the frame G is moved toward and from the feeding mechanism and is held in the position to which it is adjusted, so as to insure the proper piling of the sheets of paper.

The frames J supporting the joggers i and guards h are laterally adjustable so as to conform to the width of the paper and in the present instance there is a bar J' on which the frame J slides and this bar has teeth j on its upper surface and meshing with the teeth is a pinion j' on a shaft J^2 having a handle j^3 . On turning the handle the frames J can be adjusted toward and from each other. The jogging motion is imparted to each shaft I by a cam v on a shaft V. This cam engages the arm i' on the shaft i and causes the shaft to rock. In the present instance, the arm i' has two rollers i^2 —one located on each side of the cam v , but other connections may be used without departing from the essential features of the invention. The shaft V is driven by the rollers d .

On the shaft V is an eccentric v' , having a strap which is connected to a rod v^2 , which, in turn, is connected to a rock arm w having a series of joggers w' which act to force the sheet of paper after it is freed from the feed belts D and F toward the stop g and alternating with these joggers are guides w^2 which hold the sheets of the pile of paper in the proper position, as shown in Fig. 5.

In order to feed the sheet of paper properly to the pile, I preferably arrange means for slightly turning up the sides of the sheets of paper so as to stiffen it as it is released from the control of the feed belts and thus the paper will pass evenly to the stop and will lie properly upon the pile. In order to accomplish this, I provide rollers g , which project into the path of the paper at the edge of each sheet and these rollers are carried by arms Q adjustably mounted on a cross bar Q'. Directly back of each roller is a guide V' which is formed as shown and slightly bends the edge of the sheet so that the sheet, when projected from the feeding mechanism, will lie evenly on the pile.

While the feed belts D and F may, in some instances be single belts, I prefer to make them, as shown clearly in Figs. 2 and 6; there being, in this instance, a series of 5 lower belts *d* which pass around individual drums on their respective shafts and there are narrow belts *f*, which are spaced a given distance apart and the fixed guide V' and roller *q* are located in such a position as to 10 properly curl the edges of the paper for the purpose described above. In some instances the rollers and guides may be so located as to bend the sheet at the center instead of at the edges producing good results. Instead of 15 vertically moving the platform as the height of paper increases I may locate the platform in a fixed position and raise the arm carrying the feed mechanism, as clearly shown in Fig. 7, in which B² is the platform 20 and A² is a frame mounted on the standard A³ and this frame carries the feed belts F' and D'.

N' is the suction pump.

M' is the diaphragm casing having a diaphragm connected to the lever K' and the ratchet wheel is on a shaft P³ around which passes a chain *a*⁴ connected to the sliding frame A². Carried by the frame A² is a guide *a'* for the paper and in 30 this guide is a port *a*² communicating with the suction pump through a tube *a*³, so that as the pile of paper increases and the port *a*² is partially closed, the suction pump will 35 operate the diaphragm which, in turn, will cause the feed mechanism to raise the frame A² and with it the feed belts. This is the same principle as is illustrated in the construction shown in Figs. 1 and 2, only the 40 platform is moved instead of the feeding mechanism.

The operation of the mechanism illustrated in Figs. 1 and 2 is as follows:—The platform B is suspended in position in front of the feed mechanism and the web of paper 45 is fed through the mechanism and is cut into proper lengths to form the sheets desired. The side guides, end stops, and joggers have all been adjusted. The severed sheet is fed by the two sets of feed belts D and F and as 50 the pile of paper on the platform increases in height it will partially close the port *h'*; causing the suction pump to draw the diaphragm down, thus throwing the pawl into operative position. The eccentric will then 55 cause the pawl to turn the ratchet wheel which will lower the platform B so that the top of the pile of paper will be sufficiently clear of the port *h'* to allow sufficient air to pass through the port to supply the suction 60 pump. Thus it will be seen that the mechanism automatically controls the position of the platform and the pile of paper, always insuring the proper relation between the pile 65 and the feeding mechanism. Thus the sheet of paper is properly laid upon the pile. I

preferably slightly arch the sheet by the use of the roller *q* and guide V' so as to slightly stiffen the sheet in order that it may be properly placed upon the pile. The guides and joggers are readily adjusted so 70 as to accommodate sheets of different sizes. After the pile of paper on the platform B has reached the proper height, then the platform is lowered on to the truck E and the paper conveyed to any point desired; another platform being placed in position to 75 receive another pile of paper. It will be understood that where the web of paper is cut into longitudinal strips and these strips severed so as to form separate piles that the 80 height of the piles is controlled by the pile in close proximity to the port communicating with the suction pump.

I claim—

1. The combination in a lay boy, of a 85 platform; means for feeding sheets of paper to the platform; means for vertically moving one of said elements with respect to the other; suction mechanism, for actuating said means, having an inlet opening above 90 the platform and in close proximity to one side of the pile of paper; the paper acting as a valve to regulate the amount of air passing to the suction device so that when the pile increases in height the means for 95 moving one of said elements, with respect to the other, will be actuated.

2. The combination in a lay boy, of a platform; means for feeding sheets of paper to the platform; automatic pneumatic means 100 for governing the position of the top of the pile of paper in respect to the feeding mechanism; a suction pipe connected to the pneumatic means and located in close proximity to the pile of paper so that as the pile increases in height the opening in the pipe is 105 gradually closed; the pneumatic means being actuated to lower the height of the pile of paper so as to expose more of the opening in the suction pipe.

3. The combination in a lay boy, of a 110 platform; feeding mechanism for feeding sheets of paper to be piled on to the platform; a suction pump; mechanism for changing the relative position of the platform and feeding mechanism; with means for controlling the changing mechanism actuated through the medium of the suction pump; and an air passage for supplying air 115 to the suction pump located in the path of the paper so that as the pile of paper increases it will close, or partly close, the passage communicating with the suction pump, thus causing the pump to release the changing mechanism.

4. The combination in a lay-boy, of a platform; means for vertically moving the platform; feeding mechanism for feeding sheets of paper on to a pile on the platform; means for lowering the platform; a 120 130

suction pump; a diaphragm arranged to throw the said means into operative position; a guide at the side of the pile of paper; a port in the guide communicating with the suction pump so that when the height of the pile of paper is such as to close, or partially close, the port, the suction pump will actuate the diaphragm to release the lowering means; causing the said means to lower the platform; the top of the pile of paper being always maintained in proper relation to the feeding mechanism.

5. The combination in a lay-boy, of a frame; feeding mechanism carried by the frame; a platform vertically adjustable on the frame; means for lowering the platform; guides on the frame for the paper as it is fed on to the pile on the platform; a suction pump; a casing; a diaphragm in the 10 casing; a pipe leading from the suction side of the pump to one side of the casing under the diaphragm; a port in one of the guides for the paper above the platform; a pipe leading from the said port to the suction side 15 of the pump; a bell crank lever connected to the diaphragm; means for lowering the platform normally out of position so that the mechanism will only operate when the pile of paper closes, or partly closes the 20 port in one of the guides.

6. The combination in a lay-boy, of a frame; two series of endless belts through which a sheet of paper is fed; a platform; two shafts; cross bars; and chains from 25 which the platform is suspended; mechanism for turning said shafts to lower the platform; a suction pump; a supply pipe for the said suction pump having a port ad-

jacent to the pile of paper; and means controlled by the pump, for throwing in the 40 mechanism for turning the said shafts so that the platform will be automatically lowered when the top of the pile of paper reaches a given height.

7. The combination of a frame; two sets 45 of feed belts between which the sheets of paper are fed on to a pile; two overhead shafts; a platform suspended from said shafts; a ratchet feed mechanism geared to said shafts; a pawl; means for reciprocating 50 said pawl; a diaphragm; a lever connected to the diaphragm for throwing the pawl into and out of operative position; a guide for the pile of paper; a port in the guide; a casing for the diaphragm; a suction pump; 55 and a pipe leading from the port and from the under side of the diaphragm to the suction side of the pump.

8. The combination in a lay boy, of a platform; means for feeding sheets of paper 60 to the platform; means for controlling the position of the platform in respect to the feeding means and a suction device for controlling the platform mechanism; the opening of the suction device being located at 65 one side of the pile of paper and in close proximity to the edge thereof; so that the paper acts as a valve to regulate the amount of air passing to the suction device.

In testimony whereof, I have signed my 70 name to this specification, in the presence of two subscribing witnesses.

JOSEPH A. WHITE.
